(57) CLAIM

The ornamental design for a shoe, as shown and described.

DESCRIPTION

FIG. 1 is a lateral side view of a shoe showing my new design;

FIG. 2 is a medial side view thereof;

FIG. 3 is a top side perspective view thereof;

FIG. 4 is a rear view thereof;

FIG. 5 is a front view thereof;

FIG. 6 is a top plan view thereof, and,

FIG. 7 is a bottom plan view thereof.

The dot-dash broken lines, including those depicting the icons on the sole of the shoe, depict portions of the shoe that form no part of the claim. All other even-dashed broken lines depict stitching, which does form a part of the claim.
